UNITED STATES PATENT OFFICE.

DAVID H. BLOSSOM, OF SALT LAKE CITY, UTAH.

SOLAR ATTACHMENT FOR TRANSITS.

SPECIFICATION forming part of Letters Patent No. 768,729, dated August 30, 1904.

Application filed April 23, 1904. Serial No. 204,588. (No model.)

To all whom it may concern:

Be it known that I, DAVID H. BLOSSOM, a citizen of the United States, residing at Salt Lake City, in the county of Salt Lake and 5 State of Utah, have invented new and useful Improvements in Solar Attachments for Transits, of which the following is a specification.

My invention pertains to solar attachments for transits and like instruments, and contemplates the provision of such a device through the medium of which the true meridian may be expeditiously found or determined.

Other advantageous features of the invention will be fully appreciated from the following description and claims, when taken in connection with the accompanying drawings, forming part of this specification, in which—

Figure 1 is a plan view of my attachment as the same appears when applied to the object end of a transit-telescope; Fig. 2, an enlarged side elevation of the same; Fig. 2^a, a detail section taken in the plane indicated by the line 2^a 2^a of Fig. 2; Fig. 3, an elevation illustrating the side of the attachment opposite to that shown in Fig. 2; Fig. 4, a front elevation of the attachment; Fig. 4^a, a detail section taken in the plane indicated by the line 4^a 4^a of Fig. 4; Fig. 5, a vertical section taken through the longitudinal center of the attachment; Fig. 6, a detail front elevation illustrative of the scale on the forward end of the body of the attachment, and Fig. 7 a detail plan view illustrating the reflector comprised in the attachment and the spirit-level and the milled head fixed on the trunnions of the reflector.

Similar letters designate corresponding parts in all of the views of the drawings, referring to which—

40 A is the object end of a transit-telescope, which is provided at *a* with a mark, and B is the body of my novel solar attachment. The said body B may be of any construction compatible with the purposes of my invention 45 without involving a departure from the scope thereof. I prefer, however, to have it comprise a cap *b* and a tubular portion *c*, cast or otherwise formed in one piece, as clearly shown in Fig. 5. The cap *b* is of a size to receive the object end A of the transit-telescope

and is provided with resilient clamps *e e'*, which form part of its side wall, and is also provided on the clamp *e* with a lug *f*, having a transverse threaded aperture, and on the clamp *e'* with a lug *g*, having a plain transverse aperture. Journaled in and held against endwise movement with respect to the lug *g* is a screw *C*, which extends through the threaded aperture in the lug *f* and is designed to set the clamps *e e'* against the object end of the telescope, and thereby fix the cap on the telescope. The cap *b* is further provided with the mark *h*, which in connection with the mark *a* of the telescope serves to enable the operator to quickly and easily position the attachment on the telescope. As best shown in Fig. 5, the tubular portion *c* of the body B is provided with a beveled forward end *i*, bearing a scale *j*; Fig. 6, a circumferential groove *k*, located immediately in rear of said beveled end, a smooth bore *l*, and an interiorly-rabbeted inner end *m*.

D is a resilient clamping-band surrounding the tubular portion *c* of the body B and arranged in the circumferential groove *k* of said tubular portion and having a threaded aperture *n* in one of its ends and a smooth aperture *n'* in its other end, Fig. 4, and also having a radial lug *p* located at a point remote from the said ends.

E is a screw which extends loosely through the aperture *n'* of the clamp and engages the aperture *n* and is provided with a shoulder *q*, bearing against the clamp end in which the aperture *n'* is formed, and also with a milled head *r*. By turning the said screw E in one direction the clamping-band may obviously be fixed against movement on the tubular body portion *c*, while by turning the screw in the opposite direction the band may be rendered free to turn around on said portion *c*.

F is an axially-movable tube which is journaled in the tubular portion *c* of the body B and is provided at its forward end with a flange *s*, disposed against the forward end of said tubular body portion and at its rear end with a reduced and exteriorly-threaded portion *t*, this latter for the engagement of an interiorly-threaded annulus *u*, which is disposed in the rabbet *m* of the tubular body portion *c*.

and serves to hold the tube F against forward movement in the tubular body portion c without interfering with the rotary or axial movements of said tube. The bore of the tube F is preferably tapered toward the rear end thereof, and the tube is provided at its forward end with forwardly-reaching arms v and on its perimeter with lugs w w'. The lug w is provided with a transverse threaded aperture, as is also a lateral projection x on the lug, while the lug w' is also provided with a transverse threaded aperture, Fig. 4^a. In the threaded aperture of the lug w and the projection x thereon bears a screw G, which has its inner end arranged to engage one side of the lug p on the clamping-band D and is provided at its outer end with a milled head y, while in the threaded aperture of the lug w' is arranged the threaded inner end of a housing z. This housing contains an endwise-movable hollow plunger a', which is designed to be pressed by a spring b' against the opposite side of the lug p with reference to the screw G. In virtue of this construction it will be observed that when the clamping-band D has been fixed on the tubular portion c of the body B a nice adjustment of the tube F with respect to the tubular portion c may be effected by turning the screw G toward the right, since said screw by pressing against the lug p of the fixed clamp will cause the tube F to slowly revolve toward the left—i. e., in a direction opposite to that in which the screw is moved. Incident to the described slow rotation of the tube F through the medium of the screw G the plunger a' will be forced into the housing or casing z against the action of the spring b', which will be compressed. From this it follows that to revolve the tube F in the opposite direction it is simply necessary to turn the screw G to the left, when the plunger a', acting against the lug b, will turn the tube F in the direction opposite to that in which the plunger moves. In this connection it is well to state that the rotatable tube F is provided with a mark or pointer c', designed to coöperate with the scale j on the beveled forward end of the tubular body portion c, this to enable the operator to accurately position the said tube with respect to the said tubular body portion. Scale j also serves as an hour-circle to enable operator to determine the time, either A. M. or P. M.

H is an opaque reflector, preferably of dark glass or polished metal, which is so arranged relative to the tube F as to obscure but one-half of the field of the telescope, this being materially advantageous, since it obviates the necessity of adjusting or disturbing any of the parts of the attachment after the true meridian is found or determined. The reflector is also so positioned with reference to the tube F that it can be placed in any one of the five positions in the field of the telescope—

viz., the upper half, the lower half, the center, the right half, or the left half. In virtue of the reflector being opaque the possibility of a double refraction or double image is obviated, which is an important advantage. 70

I is a rocking body interposed between the forwardly-reaching arms v of the tube F and carrying the reflector H, the said reflector being preferably of dovetail form in cross-section and set and secured in a correspondingly-shaped recess in the rocking body I, as shown in Figs. 4 and 7. The said rocking body I is provided at one end with a trunnion d', which is journaled in one of the arms v and is provided with a milled head f', through the medium of which the body may be quickly rocked to position the reflector. At its opposite end the body I has a trunnion g, which is journaled in the other arm v and is provided at the outer side of the arm with a platform h'. This platform h' has apertures i' (see dotted lines in Fig. 3) to receive screws j', depending from a spirit-level J, and on the said screws j' below and above the platform h' are nuts k', through the medium of which the spirit-level may be positioned and adjustably fixed with respect to the said platform a'. From the foregoing it follows that the spirit-level rocks with the rocking body I and the reflector H on said body, and as the level-bubble reads to thirty seconds of arc the one-half sun's declination (plus or minus refraction) can be directly transferred from the vertical circle of the transit bearing the attachment to the reflector of the attachment without sighting at targets or other objects, which is an important desideratum. 90

As before stated, the body I and the reflector H may be rocked to the approximate angle desired through the medium of the milled head f'; but in order to accurately determine the angle of the reflector I provide the construction best shown in Figs. 2 and 2^a. This construction comprises a lever K, loosely mounted on the trunnion d', a screw L, bearing in the lever and arranged to be set against the trunnion so as to fix the lever thereon, a housing or casing M, screwed into a lateral lug N on the tube F, a spring-pressed plunger P movable in the casing M and bearing at its lower end against the lever K, a sleeve Q, screwed at its upper end into a lateral lug R on the tube F and having an interior thread at its lower end and also having a mark on its outer side, and a screw S, which bears in the said sleeve Q and is arranged to bear at its upper end against the under side of the lever K. The screw S is fixed in or formed integral with a tube T, which is of a size to receive the sleeve Q and is provided with a beveled upper end and also with graduations U from "0" to "5," designed to be read in connection with the mark on the said sleeve Q with a view of enabling the operator to accurately place the reflector H in the position de- 130

sired. When the screw S and its tube T are turned toward the right, the lever K will obviously be moved upwardly, as will also the plunger P, and the spring backing said plunger will be compressed, while when the screw S and its tube T are turned toward the left said screw and tube will be moved downwardly, and the lever K will also be moved downwardly under the action of the spring 5 behind the plunger P. It will also be noticed that when the screw L is out of engagement with the trunnion d' the lever K will remain idle and will in no measure interfere with the adjustment of the reflector through the medium of the milled head f'.

In the practical use of my novel attachment the same is placed on the object end of a perfectly-adjusted transit and is fixed with the mark h on its body B in alinement with 10 the complementary mark on the transit-telescope. With this done the transit and the main-telescope bubble are leveled, the tube F is turned so that the hour-angle reads "12," and is fixed in such position through the medium of 15 the clamping-band D and screw E and tangent-screw G. The spirit-level J is brought to center to correspond with the level of the main telescope, an angle is set off on the vertical circle of the main telescope equal to one-half of the sun's 20 declination, (corrected for refraction,) the telescope being of course elevated when the sun is south of the equator and depressed when the sun is north of the equator, the small bubble of the spirit-level J is brought to 25 center and fixed in such position, the latitude of the place is set off on the vertical circle of the transit, and the telescope is pointed toward the south, after which the revolving motion of the solar and the horizontal motion 30 of the transit are unclamped and both are moved until the sun's reflection appears in the square of the solar hairs of the transit and the transit is clamped, when the telescope will be on the meridian. With this done a sight 35 may be taken without disturbing the solar in any way.

It will be appreciated from the foregoing that my novel attachment is adapted for use on any transit equipped with a vertical circle 40 reading to single minutes of arc; also, that the attachment is so constructed that its position as regards upper side and lower side will always be the same relative to the transit-telescope, this being materially advantageous, since it obviates the necessity of adjustment every time the attachment is employed.

Because of the graduations on the tube T—*i. e.*, the graduations "0" to "5," and ten 45 small graduations between each couple of numbered graduations—it will be observed that in revolving the said tube each small division moves the reflector through one-half minute of arc. A large division from "0" to "1," for example, moves reflector through

five minutes of arc, and a complete revolution from "0" to "0" moves reflector through thirty minutes of arc. This is for the purpose of changing the declination-angle without referring to the level-bubble after the 50 reflector is first set at a known angle.

The projections a' on the body portion b are designed to bear against the shoulder of the transit-telescope, against which the cap and sunshade rest, Fig. 2, with a view of preventing the front of the body portion b from coming in contact with the object-glass of the telescope or the ring that holds it and gives a more secure bearing for positioning the solar attachment.

The journals in the arms v are to be so constructed that the body I may be adjusted so that the reflector when in a vertical position with main-telescope level will be perpendicular to the line of collimation of the transit.

By tightening the annulus u any wear that may occur between the tubular body portion c and the tube F may be taken up by cutting back the flange s.

I have entered into a detailed description 90 of the construction and relative arrangement of the parts embraced in the present and preferred embodiment of my invention in order to impart a full, clear, and exact understanding of said embodiment. I do not desire, 95 however, to be understood as confining myself to such specific construction and relative arrangement of parts, as such changes or modifications may be made in practice as fairly fall within the scope of my invention 100 as claimed.

Having described my invention, what I claim, and desire to secure by Letters Patent, is—

1. The combination with the telescope of a 105 transit; of a reflector and a level carried by the telescope; the said reflector and the level being fixed with respect to each other and movable together and with respect to the telescope.

2. The combination with the telescope of a transit; of a reflector and a spirit-level carried by the telescope; the said reflector and the level being fixed with respect to each other, and rotatable together and with respect to 115 the telescope.

3. A solar attachment for transits and similar instruments, comprising a suitable support, a reflector having trunnions journaled in the support, and a spirit-level mounted on 120 one of the trunnions of the reflector, and movable with said reflector.

4. A solar attachment for transits and similar instruments, comprising a suitable support, a reflector having trunnions journaled 125 in the support, a spirit-level mounted on one of the trunnions of the reflector and movable with said reflector, and a head fixed on the other trunnion of the reflector.

5. The combination of a tube having for- 130

wardly-reaching arms, a reflector interposed between the said arms, and having trunnions journaled therein, and a spirit-level on one of the trunnions of the reflector.

5 6. The combination of a tube, and a rotatable reflector mounted so as to rest parallel to the line of collimation of the tube when it extends in the same direction as the tube.

7. The combination of a tube having a scale 10 at its forward end, and a second tube movable axially with respect to the first-mentioned tube, and carrying a reflector, and provided with a pointer arranged to coöperate with the scale of the first-mentioned tube.

15 8. The combination of a tube having a scale at its forward end, a second tube supported by and movable axially with respect to the first-mentioned tube and provided with a pointer arranged to coöperate with the scale 20 of the first-mentioned tube, a rotatable reflector mounted in the second-mentioned tube, and a spirit-level connected and rotatable with the reflector.

9. The combination of a tubular body portion, a tube supported by and movable axially with respect to the said tubular body portion, a rotatable reflector carried by said tube, a spirit-level connected and rotatable with the reflector, and means for adjusting the tube on 25 and adjustably fixing the same with respect to the tubular body portion.

10. The combination of a tubular body portion, a tube supported by and movable axially with respect to the said tubular body portion, a reflector carried by said tube, a resilient clamping-band mounted on the tubular body portion and having a lug, a screw connecting the ends of the said resilient clamping-band, means connected with the 35 tube and bearing against one side of the lug on the clamping-band for moving the tube axially in one direction, and means carried by the tube and bearing against the opposite side of the lug on the clamping-band for moving 40 the tube axially in the opposite direction.

11. The combination of a tube, a rotatable reflector mounted in the tube, a lever connected with the reflector, a spring-pressed plunger carried by the tube and bearing 45 against one side of the lever, a sleeve also carried by the tube and provided with a pointer and an interior screw-thread, a screw

bearing in said sleeve and arranged to engage the opposite side of the lever, with reference to the plunger, and a tube carried by 55 the screw and arranged to receive the sleeve; said tube having a scale arranged to coöperate with the pointer of the sleeve.

12. The combination of a sleeve provided with an interior screw-thread and an exterior pointer, and a screw bearing in said sleeve and having a tube which receives the sleeve and is provided with a scale adapted to coöperate with the pointer thereof.

13. The combination with the telescope of 60 a transit; of a solar attachment comprising a cap removably arranged on the object end of the telescope; said cap having spring-clamps forming part of its side wall, and also having adjustable means connecting the free ends 70 of the said clamps.

14. The combination of a tubular body portion, a tube supported by and movable axially with respect to the said tubular body portion, a pointer on the one and a scale on 75 the other whereby the position of the tube may be accurately determined, a reflector carried by the tube, and suitable means for adjustably fixing the tube with respect to the tubular body portion.

80 15. The combination of a tubular body portion, a tube supported by and movable axially with respect to the said tubular body portion, a pointer on the one and a scale on the other whereby the position of the tube 85 may be accurately determined, means for adjustably fixing the tube with respect to the tubular body portion, a rotatable reflector carried by the tube, a spirit-level connected and rotatable with the reflector, and means 90 for adjustably fixing the reflector against rotation.

16. The combination of a tube, a rotatable, opaque reflector mounted in alinement with the tube and obstructing only half the field 95 of view, and a spirit-level connected and rotatable with the reflector.

In testimony whereof I have hereunto set my hand in presence of two subscribing witnesses.

DAVID H. BLOSSOM.
